UNITED STATES PATENT OFFICE.

WILLIAM M. CAMP, OF PAWTUCKET, RHODE ISLAND.

BOTTLE-STOPPER.

1,111,294.

Specification of Letters Patent. Patented Sept. 22, 1914.

Application filed August 16, 1912. Serial No. 715,448.

To all whom it may concern:

Be it known that I, WILLIAM M. CAMP, citizen of the United States, residing at Pawtucket, in the county of Providence and 5 State of Rhode Island, have invented certain new and useful Improvements in Bottle-Stoppers, of which the following is a specification.

This invention relates to stoppers or closures for bottles, jars and similar containing vessels and has for its object the provision 10 of a comparatively simple and thoroughly efficient device of this character capable of being readily applied to the neck of a bottle 15 or jar and which will hermetically close the mouth thereof so as to effectually prevent the entrance of air to the interior of the vessel.

A further object of the invention is to provide 20 a stopper or closure including an expandable clamping member adapted to embrace the neck of a vessel for the purpose of holding the closure in position over the mouth thereof.

25 A further object is to provide a closure, the cap of which is formed with spaced depending arms having seating grooves formed therein for the reception of a clamping member or ring whereby, when the ends 30 of the ring are drawn together, the arms will be forced into engagement with the neck of the bottle.

A further object is to provide a locking lever having pivotal connection with one end 35 of the clamping member or ring and adapted to engage and contract the other end of said ring when the lever is moved to operative position.

A still further object of the invention is 40 generally to improve this class of devices so as to increase their utility, durability and efficiency, as well as to reduce the cost of manufacture.

Further objects and advantages will appear 45 in the following description, it being understood that various changes in form, proportions and minor details of construction may be resorted to within the scope of the appended claims.

50 For a full understanding of the invention and the merits thereof, reference is to be had to the following description and accompanying drawing, in which:

Figure 1 is a vertical sectional view of a bottle provided with a cap or closure constructed in accordance with the present invention; Fig. 2 is a side elevation thereof; Fig. 3 is a perspective view of the cap detached; Fig. 4 is a similar view of the clamping ring detached; Fig. 5 is a side elevation 60 illustrating a modified form of the invention; Fig. 6 is a perspective view of the retaining device shown in Fig. 5 removed from the neck of the bottle.

Corresponding and like parts are referred 65 to in the following description and indicated in all the views of the drawing by the same reference characters.

The improved stopper or closure forming the subject matter of the present invention 70 is principally designed for attachment to bottles, jars and similar liquid containing vessels, and by way of illustration is shown in connection with a bottle of the ordinary construction in which 5 designates the neck, 75 6 the mouth and 7 an annular groove formed in the neck of the bottle immediately below the mouth thereof.

The device comprises an expandable clamping member or ring 8, preferably 80 formed of a single length of spring wire, one end of which is bent to produce a hook 9, the bill of which opens outwardly, as shown. That portion of the clamping member or ring 8, directly opposite the closed 85 end of the hook 9 is bent to produce a loop 10 and then continued downwardly and laterally to form an arm 11 terminating in an angularly disposed lug constituting a keeper 12.

90 Mounted on the clamping member 8, is a closure, preferably in the form of a cap 13 provided with a depending flange 14 having spaced vertically disposed arms 15 extending downwardly therefrom and terminating 95 in arcuate plates 16. The arms 15 are provided with transverse grooves 17 adapted to form a seat for the clamping member or ring 8, so that when the ends of the clamping member are drawn together, the arms 100 15, as well as the plates 16, will be securely clamped into engagement with the neck of the bottle at the groove 7 therein. The upper edges of the plates 16 are inclined downwardly at 18 and the metal at the upper corner of each plate pressed laterally to

produce offset ears 19 which bear against the clamping member or ring and serve to prevent accidental displacement thereof.

As a means for drawing the ends of the clamping member together to retain the cap in position on the mouth of the bottle, there is provided a locking lever 20 also preferably formed of a single length or strand of wire, one end of which is provided with an eye 21 which encircles the clamping member at the loop 10, while the other end thereof is bent to produce a handle 22. That portion of the locking lever adjacent the eye 21 is provided with a curve or bend 23 adapted to engage the hook 9 for the purpose of contracting the ring when the lever is moved into engagement with the keeper 12. A disk of cork, felt or similar material 24, is preferably disposed within the cap 13 and retained in position thereon by means of the flange 14, said cap being adapted to bear against the mouth of the bottle so as to hermetically close the same and thus prevent the entrance of air to the contents thereof.

In operation, the cap is placed on the mouth of a bottle, after which the bent portion 23 of the locking lever is passed over the hook 9 and said lever swung laterally until it engages the keeper 12 and in which position the arms 15 and ring 8 will be firmly clamped within the groove 7 of the neck of the bottle, while the arcuate plates 16 will bear against that portion of the neck of the bottle immediately below the groove, as best shown in Fig. 1 of the drawing.

It will here be noted that as the ring is compressed, said ring will be forced downwardly beneath the offset ears 19 so as to effectually prevent accidental displacement of the ring. When it is desired to remove the cap of the bottle, it is merely necessary to disengage the locking lever from the keeper or lug 12 and swing said lever upwardly then the clamping member or ring will automatically expand and thus permit the cap to be readily detached from the bottle.

In Figs. 5 and 6 of the drawing, there is illustrated a modified form of the invention in which the cap 13 is dispensed with, the clamping member or ring being provided with a transverse retaining bar 25 adapted to extend across the mouth of the bottle and bear against the usual cork or closure to prevent accidental displacement thereof. The bar 25 is preferably formed of wire and is provided at its opposite ends with terminal eyes 26, which engage offset portions 27 formed in the clamping member to prevent relative movement of the bar with respect to said ring. In this form of the device, the bar 25 not only serves as a closure or retaining means for the ordinary cork or stopper of the bottle, but by engagement with the clamping ring, serves to impart additional resiliency thereto as said bar must be

slightly bowed in order to draw the ends of the clamping member together, as will be readily understood.

The stoppers or closures may be made in different sizes and shapes and applied to any style of bottle, jar or similar containing vessel without departing from the spirit of the invention.

Having thus described the invention, what is claimed as new is:

1. A bottle closure including a cap, an expansible clamping member having one end provided with a hook and an intermediate portion thereof formed with a loop having an extension terminating in an angularly disposed lug constituting a keeper, means carried by the clamping member and adapted to extend across the mouth of a bottle, and a locking lever pivotally mounted on the loop and having one portion thereof adapted to engage the hook and another portion thereof movable into engagement with the keeper for clamping said member in contact with the neck of the bottle.

2. As a new article of manufacture, a bottle closure including a cap, a clamping ring having means for engagement with the mouth of a bottle and formed of a single length of wire having one end thereof bent to form a hook, that portion of the wire opposite the hook being bent to produce a loop and thence extended downwardly and laterally to form an arm terminating in an angularly disposed lug constituting a keeper, and a locking lever having one end thereof pivotally mounted on the loop and provided with a curved portion adapted to engage the hook and draw the two ends of the ring together when the free end of the lever is moved into engagement with the keeper.

3. A cap securing device for bottles including a cap formed with an annular groove, a locking member comprising a strand bent to partially embrace the cap and disposed within the groove of the same, one terminal of said member being bent upon itself to form a loop, the other terminal of said member being bent upon itself and extending beyond the bent portion, the terminal of the extension being disposed at right angles to its body portion, a locking bail embracing the looped portion of said other terminal and extending through the loop of the first mentioned terminal, said locking member being disposed to draw the terminals together and be maintained against movement by the extension of the second-mentioned terminal.

4. A cap supporting device for bottles including a cap formed with an annular groove, the material from which the cap is formed adjacent said groove being resilient, a clamping member comprising a strand of resilient material bent to embrace the cap and disposed within the groove formed therein, one

terminal of the said strand being looped, the other terminal of the strand being rebent to produce a loop and a straight portion, the terminal of which is disposed at right angles 5 to its body portion, a locking bail embracing the loop of the second-mentioned terminal, said locking bail being disposed to draw the terminals of the clamping member together, the second mentioned terminal of

the clamping member holding the locking bail against movement after said terminals have been drawn together.

In testimony whereof I affix my signature in presence of two witnesses,

WILLIAM M. CAMP. [L.S.]
